(57) **CLAIM**

The ornamental design for an electrical connector, as shown and described.

DESCRIPTION

FIG. 1 is a front, top and right side perspective view of an electrical connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a partial enlarged view of the elliptical area shown in FIG. 1; and,

FIG. 9 is a partial enlarged view of the elliptical area shown in FIG. 2.

The broken line portion of the figure drawings is included to show unclaimed subject matter only and forms no part of the claimed design. The dash-dot lines represent the boundary of the claimed design.
